UNITED STATES PATENT OFFICE

ARNOLD G. PARKER, OF FLUSHING, NEW YORK, ASSIGNOR TO CONRAD H. MATTHIESSEN, JR., OF NEW YORK, N. Y.

AEROPLANE

Application filed July 9, 1928. Serial No. 291,174.

This invention relates to an aeroplane construction in which the cylinders of the engine are supported outside of the wing, i. e. either above or below the wing, the engine being an air-cooled, slide valve, internal combustion engine. The invention also relates to means for supplying cooling air transversely to the cylinders of an engine, which extend parallel to the longitudinal axis of the aeroplane, at right angles to the propeller, regardless of where the cylinders are supported with relation to the aeroplane wing, and to means for controlling the air supplied to said cylinders.

The engine cylinders are arranged within the line of flight and extend substantially parallel to the longitudinal axis of the aeroplane, at right angles to the propeller, and a shaft also parallel to the longitudinal axis of the aeroplane, drives the propeller and preferably the harmony drive shaft of the engine drives the propeller. This harmony drive shaft serves as a driving connection to the valve shaft, which is driven at half speed with relation to the engine crankshaft.

One object of the invention is to combine the engine cylinders, which extend parallel to the longitudinal axis of the aeroplane, at right angles to the propeller, with the wing of an aeroplane, so that the cylinders may be supported outside of the wing.

Another object of the invention is to provide means for controlling the cooling of the engine regardless of where the cylinders are supported with relation to the wing, by means of shutters or louvres arranged in the cowling of the engine, and by causing the air, when the plane is in flight, to pass transversely across the cylinders. The passage of the air across the cylinders may be either from below up or the reverse.

With the above and other objects in view, my invention consists in the parts, improvements and combinations more fully pointed out hereinafter.

Turning now to the drawings:

Figure 1 is a top plan view of an aeroplane, showing the engine mounted below the wing.

Figure 2 is a vertical cross-sectional view of the form shown in Figure 1.

Figure 3 is a detail of the worm gearing used between the engine and the propeller shaft.

Figure 4 is a detail front elevation showing the engine mounted below the wing, head on.

Figure 5 is a top plan view of an engine mounted outside the wing, and

Figure 6 is a longitudinal, sectional view of the engine, mounted in the fuselage of the aeroplane, and arranged so that visibility is afforded to the aviator, and showing the means for air cooling the engine.

The aeroplane wing 1, is preferably made of metal and has the usual ailerons 1^a. It is provided with covering 2, and has brackets 3, which take up the thrust of the propeller, 65 spars 4, and struts 5. The wing may be embodied in a monoplane or multiplane. If embodied in a monoplane, it may be mounted above or below or midway of the fuselage.

The engine is a slide valve internal combustion engine like that shown in Patents 1,492,573 and 1,617,019, to C. H. Matthiesen, jr., in which both the valve shaft and the engine crankshaft develop power.

In the form of the invention shown in Figures 1 to 5, the engine is suspended from a wing by means of supports 6, which are connected at 7, to the spars 4, and are also connected to crosspiece 8, and the engine frame at 9. Struts 10 and 11, attach the engine to the spars and take up the side thrust reaction of the propeller.

The wing may be made metallic to avoid the danger of burning the wing by an air-cooled engine. Or that part of the wing on which the engine is mounted may be made of metal and the rest of the wing may be made of wood.

In the engine illustrated, the power developed by both the valve shaft and the

crankshaft, is transmitted to the propeller shaft.

As shown, the engine 12, is provided with four cylinders 13, 14, 15 and 16, which are arranged side by side. The number of cylinders may be varied. The cylinders extend in the line of flight, parallel to the longitudinal axis of the aeroplane and at right angles to the propeller, and the heads of the cylinders are arranged head on, as shown in Figure 4. The cylinders are preferably provided with heat radiating fins 18, and the cooling air passed transversely to them or longitudinal fins may be used and the air passed longitudinally over the cylinders, or spiral fins may be used and the air passed spirally over the cylinders.

By arranging the cylinders parallel to the longitudinal axis of the aeroplane, at right angles to the propeller and mounting the engine above or below the wing of the aeroplane, a compact structure is obtained. The air resistance offered by the engine and its cowling is thus much reduced.

As shown the engine crankshaft 19, extends in the rear of the cylinders, transversely of the longitudinal axis of the aeroplane. The crankshaft extends in a substantially horizontal plane when the aeroplane is in starting position on the ground. The crankshaft carries a plurality of cranks 20, and connecting rods 21, one each for each cylinder of the engine, which cranks and connecting rods are reciprocated by working piston 22, in each cylinder (see Figure 1).

As illustrated, the shaft for driving the propeller is preferably the harmony drive shaft, which serves as a driving connection to the valve shaft, the latter being driven at half speed with relation to the engine crankshaft. The harmony drive shaft is mounted parallel to the longitudinal axis of the aeroplane and is geared to and driven by the engine crankshaft 19, by means of worm 24, carried by the crankshaft and worm wheel 25, carried by the harmony drive shaft 23.

Mounted in front of the heads of the engine cylinders is a transverse valve shaft 26, which extends parallel to the crankshaft and carries a plurality of cranks and connecting rods, one each for each cylinder of the engine, for reciprocating plug 27, and sleeve valve 28, of each cylinder. Gas may be supplied from a fuel tank (not shown) through a suitable carburetor 29, to the intake manifold 30 and inlet 31 of each cylinder, and the exhaust gases are taken away from the exhaust port 32, by means of exhaust manifold 33, and pipe 34.

Valve shaft 26, carries a worm 35, which is engaged by worm wheel 36, carried by the harmony drive shaft 23. The power developed by the valves, during the explosion cycle, will thus be transmitted by the valve

shaft 26, to the shaft 23, to drive the propeller.

The harmony drive shaft 23, in the form shown carries the propeller hub 37, on its forward end, to which hub, propeller blades 38, are secured. The propeller may be mounted behind the engine, if desired, and then serve as a pusher, instead of a puller, as shown.

As shown, the relation between gears 24, and 25, is 1 to 2, and the relation between gears 35, 36, is 1 to 1, so that the harmony drive shaft, which drives the propeller serves as a driving connection for the valve shaft 26, which is driven at half speed with relation to the engine crankshaft.

A propeller spinner 39, carried by the hub, encases the hub, as usual, and rotates with the propeller. The engine is provided with casings 40, 41, and studs 42, connect the engine casings together, thus leaving the cylinders exposed to the air currents. A bridge 43, for the propeller shaft also extends between the two casings. Magneto 44, supply the current for spark plugs 46.

Means are provided for passing cooling air transversely across the cylinders of the engine and for controlling the passage of the air. The means for supplying and controlling the cooling air may be used with the cylinders of an engine which may be provided with either poppet or slide valve mechanism.

In the preferred form shown, the engine is provided with suitable cowling 46, which has a central portion 47, which meets the spinner 39, so as to form a streamline, and side portions 48. The side portions of the engine cowling are provided with shutters or louvres 49. The shutters are controlled manually by the aviator or may be controlled automatically. A deflector plate 50, deflects the air, so that it travels through the shutters downwardly across the cylinders and out of the aeroplane. As shown the shutters are arranged in the top of the cowling but they may be arranged in the bottom of the cowling to allow the cooling air to pass upwardly across the cylinders and be deflected over the wing being assisted by the vacuum produced above the wing, thus reducing the formation of ice on the wing. An advantage of the shutter construction is that if one of the engines of a multi-motored plane goes dead, the shutters for that engine may be closed and by reason of the streamline shape of the cowling less air resistance to the dead engine will be offered.

In the form of the invention shown in Figure 6, the engine and propeller are mounted in the nose of the fuselage. The same parts are referred to by the same reference numerals. The engine is suitably supported by mounting 51, and the shutters are operated by connecting links 52, connected to them by levers 53, so that the shutters may be opened or closed by flexible cable 54, passing around

drum 55, provided with hand crank 56, which is controlled by the aviator manually or may be controlled automatically.

As shown in this figure, a clear vision is afforded to the aviator.

Having thus described the construction, the operation will be clear. It will be understood, however, that changes may be made in carrying the invention into effect, without departing from the principle thereof.

What I claim is:

1. In an aeroplane the combination with a wing and propeller, of a slide valve engine, said engine being provided with cylinders, a crankshaft and a valve shaft, both of which shafts develop power, a harmony drive shaft geared to said crankshaft, and said valve shaft, the propeller being secured to said harmony drive shaft, said cylinders being mounted at right angles to the propeller, and means for mounting the engine outside the wing of an aeroplane.

2. In an aeroplane, the combination with a wing and propeller of a slide valve engine, said engine being provided with cylinders, a crankshaft and a valve shaft, both of which shafts develop power, a harmony drive shaft geared to said crankshaft and to said valve shaft, the propeller being secured to said harmony drive shaft, said cylinders being mounted at right angles to the propeller, and means for mounting the engine below the wing of an aeroplane.

3. In an aeroplane the combination with a wing and propeller of an engine, whose cylinders lie in the line of flight, said engine being provided with a crankshaft, a shaft geared to the crankshaft, said last named shaft extending in the line of flight, the propeller being secured thereto, said cylinders being mounted at right angles to the propeller, cowling enclosing said cylinders and means for supplying cooling air transversely to said cylinders.

4. In an aeroplane the combination with a wing and propeller of an engine, whose cylinders lie in the line of flight, said engine being provided with a crankshaft, a shaft geared to said crankshaft, said last-named shaft extending in the line of flight, the propeller being secured thereto, cowling enclosing said cylinders, means for supplying cooling air transversely to said cylinders, and a deflecting plate for guiding the air out of the aeroplane.

5. In an aeroplane, the combination with a wing and propeller, of an engine whose cylinders lie in the line of flight, said engine being provided with a crankshaft, a shaft geared to said crankshaft, said last named shaft extending in the line of flight, the propeller being secured thereto, cowling enclosing said cylinders, shutters in the cowling for admitting cooling air, and means for de-

flecting the cooling air to and transversely of the cylinders.

6. In an aeroplane, the combination with a wing and propeller, of an engine whose cylinders lie in the line of flight, said engine being provided with a crankshaft, a shaft geared to said crankshaft, said last named shaft extending in the line of flight, the propeller being secured thereto, cowling enclosing said cylinders, shutters in said cowling for admitting cooling air, means controlled by the aviator for opening and closing the shutters and means for deflecting the air transversely of said cylinders.

7. In an aeroplane the combination with a wing and propeller, of an engine whose cylinders lie in the line of flight, said engine being provided with a crankshaft, a shaft geared to said crankshaft, said last named shaft extending in the line of flight, the propeller being secured thereto, cowling enclosing said cylinders, shutters in the top of said cowling for admitting cooling air and means for deflecting the air transversely of said cylinders.

8. In an aeroplane the combination with a wing and propeller, of a slide valve engine whose cylinders lie in the line of flight, said engine being provided with a crankshaft and a valve shaft, a harmony drive shaft geared to said crankshaft and to said valve shaft, said harmony drive shaft extending in the line of flight, the propeller being secured thereto, cowling enclosing said cylinders and means for supplying cooling air transversely to said cylinders.

9. In an aeroplane, the combination with a wing and propeller, of a slide valve engine whose cylinders lie in the line of flight, said engine being provided with a crankshaft and a valve shaft, both of which develop power, a harmony drive shaft geared to said crankshaft and to said valve shaft, said harmony drive shaft extending in the line of flight, the propeller being secured thereto, cowling enclosing said cylinders, means for supplying cooling air transversely to said cylinders, and a deflecting plate for guiding the air out of the aeroplane.

10. In an aeroplane, the combination with a wing and propeller, of a slide valve engine whose cylinders lie in the line of flight, said engine being provided with a crankshaft and a valve shaft, both of which develop power, a harmony drive shaft geared to said crankshaft and to said valve shaft, said harmony drive shaft extending in the line of flight, the propeller being secured thereto, cowling enclosing said cylinders, shutters in the cowling for admitting cooling air, and means for deflecting the cooling air to and transversely of the cylinders.

11. In an aeroplane the combination with a wing and propeller, of a slide valve engine whose cylinders lie in the line of flight, said

engine being provided with a crankshaft and a valve shaft, both of which develop power, a harmony drive shaft geared to said crankshaft and to said valve shaft, said harmony drive shaft extending in the line of flight, the propeller being secured thereto, cowling enclosing said cylinders, shutters in said cowling for admitting cooling air, means controlled by the aviator for opening and closing the shutters, and means for deflecting the air transversely of said cylinders.

In testimony whereof, I have signed my name to this specification.
